PROPORTIONAL CONTROL SYSTEM

Everard M. Williams, State College, Pa.

Application January 27, 1945, Serial No. 574,940

2 Claims. (Cl. 250—2)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a radio telemetering system and more particularly to a remote control device which transmits a continuously graduated positional control.

Previously devised positional control devices have been characterized by objectionable complexity and their action has been uncertain or objectionably falsified by the influence of extraneous factors. A tone modulation on a radio carrier, to effect a remote control and to make the degree of control proportional to the intensity of modulation, has been used previously. This type of device has been found to be unreliable because of changes in signal loudness due to changes in distance between the signal transmitter and the signal receiver. Increasing this distance causes signal fading which makes the device unreliable.

In the present device two tones of different frequencies are used for the control signal. The signals may be graduated by causing one tone to increase in intensity, while the other tone decreases in intensity. At the receiver the effective response is made proportional to the ratio of the two tone intensities. With this provision in use, fading or interference affects both signals equally and their proportionate intensities are not affected. The system so operating provides a device that is characterized by a highly reliable positional control.

The objects of the present invention comprise the provision of a device that uses the ratio of the intensities of two audio tones to effect a proportionate remote control; that uses a proportionate control which ranges from values of one sense thru a null value to values of the opposite sense; and a graduated control that is free from failure due to varying carrier strength or to interference and jamming, that is positive in action and that is simple in operation, reliable and accurate.

With the above and other objects in view which will be apparent to those who are informed in the field of remote control radio system devices from the following description, an illustrative embodiment of the present invention is shown in the accompanying drawing wherein:

Fig. 1 is a block diagram and schematic view of a ground control part of the system; and

Fig. 2 is a block diagram and schematic view of an air-borne part of the system.

2

The present invention comprises as parts thereof a ground control station that is shown in Fig. 1 and a controlled station that is shown in Fig. 2 of the accompanying drawing. The ground control station that is shown in Fig. 1 comprises a control input device 1, including a manual control 4 and 5 to which a desired control is applied, a transmitter 12, and an antenna 13.

10 In the circuit that is shown in Fig. 1 of the drawing, a control that is to be transmitted is applied by hand to movable contact arms 4 and 5, that are ganged together and that engage two substantially duplicate potentiometer resistors 2 and 3. The potentiometer 2 is connected across an oscillator 6 and the potentiometer 3 is connected across an oscillator 7. The magnitude of the voltage that is supplied from oscillator 6 is equal to that supplied from oscillator 7. The 15 voltage across the potentiometer 2 is of a frequency f_2 and the voltage across the potentiometer 3 is of a frequency f_3 that differs from the frequency f_2 . The frequencies f_2 and f_3 preferably are selected to be in non-harmonic relation with respect to each other to prevent or minimize mutual interference, and particularly to prevent cross-modulation in succeeding stages of the apparatus.

20 The two ganged contact arms 4 and 5 preferably are arranged to sweep in opposite directions with respect to each other. With this provision, the voltage output of the potentiometer 2 increases as the voltage output of the potentiometer 3 decreases and conversely, as the voltage output of the potentiometer 2 decreases the voltage output of the potentiometer 3 increases.

25 The primary of transformer 55 is center-tapped at 53 to provide two sections 8 and 9. One side of potentiometer 2 is connected to one 30 end of section 8, thru lead 51 and the corresponding side of potentiometer 3 is connected thru lead 52 to section 9. A common lead 50 connects the center-tap 53 to junction 54 of contact arms 4 and 5. Thus the voltage output of potentiometer 2 is across section 8 and the output voltage of potentiometer 3 is across section 9. The secondary 10 is connected to the input of transmitter 12.

35 The degree of angular rotation of the two contact arms 4 and 5 is to be taken as being indicative of the positional control which is to be transmitted. The position that is indicated by the dotted line 11 indicates a position of null positional control at which the two voltage outputs 40 V_2 from potentiometer 2 and V_3 from potentiometer 55

eter 3 are equal to each other. When the arm 4 is positioned to the left of this null position 11 of the potentiometer 2, a positional control of positive sense will be transmitted and the ratio of V_2 to V_3 is greater than unity. When the arm 4 is positioned to the right of the null position 11 on the potentiometer 2, a positional control of negative sense will be transmitted and the ratio of V_2 to V_3 is less than unity.

The output signal from the secondary coil 13 is the output signal from the control input device 1 and is applied to a radio transmitter 12 as modulation to a carrier. The modulated carrier is transmitted from an antenna 13 part of the transmitter 12. In the course of the subsequent transmission of signal, the ratio of the two components of frequencies f_2 and f_3 is maintained equal to that between the respective outputs of the potentiometers 2 and 3, namely the ratio between V_2 and V_3 , or

$$\frac{f_2}{f_3} = \frac{V_2}{V_3}$$

The signal carrier that is emitted from the transmitter antenna 13 is intercepted by an antenna 14 of a receiver 15 and is fed as output therefrom to control output device 16.

The intercepted signal carrier comprises the signal frequencies f_2 , f_3 , in the cited example and is demodulated in the receiver 15. The output of the receiver 15 is fed in common to a desired plurality of filters 18, 19 in the control output device 16. In the control output device 16, the filter 18 isolates the signal of the frequency f_2 , and the filter 19 isolates the signal of the frequency f_3 from the modulated signal carrier output from the receiver 15.

The signal of frequency f_2 that is passed by the filter 18 is detected by a diode 20 and the rectified signal appears across a load resistor 42, connected to plate 62 of diode 20, as a direct voltage whose magnitude is proportional to the amplitude of the alternating signal of the frequency f_2 . The load resistor 42 is in series with the grid 40 of a direct voltage amplifier tube 22. Signal across the load resistor 42 is of a polarity that drives the grid 40 of the triode 22 positive. A source of negative bias, that is supplied from a contact arm 38 on a potentiometer resistor 36, is in series with the load resistor 42.

The plate current of the direct voltage amplifier tube 22 increases and decreases with the overall voltage on the grid 40 and within a certain range the variation can be made substantially linear. If it be assumed that the negative bias that is supplied at the contact arm 38 is within a predetermined range and fixed, then the variation of the plate current of the amplifier tube 22 is proportional to the variation of signal on the grid 40 and so in turn to the variation of amplitude of the component signal of the frequency f_2 in the modulation that is carried by the signal that is received by the antenna 14.

In a similar manner the component of the frequency f_3 in the output of the receiver 15 is isolated by the filter 19 in the control output device 16 and is detected by the diode 21. The rectified output appears across a load resistor 41, connected to plate 63 of diode 21, load resistor 41 being in series with the grid 39 of a direct voltage amplifier tube 23 and with a source of negative bias that is supplied from a contact arm 37 on a potentiometer resistor 35. The circuit and operation of the tubes 21 and 23 are

analogous to the circuit and operation that have been described previously for the diode rectifier 20 and the direct voltage amplifier tube 22. Variations in the plate current of the amplifier tube 22 is made proportional to the variation of amplitude of the component signal of the frequency f_2 in the modulation that is carried by the signal that is received by the antenna 14.

The plate current of the amplifier tube 22 passes thru a winding 24 connected to plate 64 of amplifier tube 22 and the plate current of the amplifier tube 23 passes thru a winding 25 connected to plate 65 of amplifier tube 23. The windings 24 and 25 comprise the split field winding of a direct current generator 26 having a rotor 27. The windings 24 and 25 are in opposition with respect to each other so that two electrical currents flowing simultaneously therein tend to set up opposing fields. When the two opposed currents in the windings 24 and 25 are equal to each other, their fields neutralize each other, and when the currents are unequal, the net field is in the direction that is determined by the stronger current. The rotor 27 of the direct current generator 26 is driven by a constant speed motor 28. The output current from the generator 26 is supplied to the rotor 39 of a direct current motor 29 having a field winding 31. A constant field is maintained in the field winding 31 of the motor 29 by a battery 32. The direction of rotation of the rotor 39 of the motor 29 is controlled by the difference between the two currents in the windings 24 and 25. The shaft 33 of the motor 29, by its rotation, exerts the positional control which the present invention is designed to effect.

A circuit including potentiometers 35, 36, and battery 34 is provided to arrest the rotation of the motor when the desired position is reached and, in the absence of any signal, to return and maintain the positional control in a neutral position. The positive terminal of battery 34 is connected thru lead 66 to the cathodes 44 and 43 of tubes 22 and 23 respectively. Shunted across the battery 34 are two potentiometers 35 and 36 which are connected so that upon movement of contact arms 38 and 37 in the same direction, the voltages tapped off with respect to the cathodes 44 and 43 vary inversely. Contact arm 38 is connected thru lead 60 and resistor 42 to the grid of tube 22, and contact arm 37 is connected thru lead 61 and resistor 41 to the grid of tube 23. Since the bias voltages are negative with respect to the cathode, no current will flow between the cathodes and grids. Consequently, the grid bias on each tube will be the sum of the bias voltage and the rectified voltage. The potentiometer contact arms 38 and 37 are mechanically connected to the rotor 39 of motor 29 by a means 33 which is shown as a shaft but may be any suitable coupling means.

In the absence of any positional control signal in the filters 18 and 19, the shaft 33 of the motor 29 will assume a definite null position, with equal biases on the grids 39 and 40 of the tubes 23 and 22, supplied from the potentiometers 35 and 36, respectively.

A positional control signal that is intercepted by the receiver antenna 14 and is fed thru the receiver 15 to the control output device 16 when its system is in balance, may be assumed to comprise a strong signal of the frequency f_2 that passes thru the filter 18 and a weaker signal of the frequency f_3 that passes thru the filter 19.

The strong signal of frequency f_2 passes from

the filter 18 to the detector 20 to which the filter 18 is transformer coupled as shown, and the weaker signal of frequency f_3 passes from the filter 19 to the detector 21 to which the filter 19 is transformer coupled, as shown. The detector 20 will pass a stronger signal to the grid 40 of the tube 22 than the detector 21 will pass to the grid 39 of the tube 23, and, as a result plate current from the tube 22 and passing thru the winding 24 will be in excess of the plate current thru the winding 25 from the plate of the tube 23 and the turning of the rotor 27 of the direct current generator 26 in the resulting field will create a voltage and current flow in the circuit of the motor armature 30.

The turning of the rotor 27 of the generator 26 generates a voltage that causes the turning of the rotor 30 of the motor 29 and of the shaft 33 of the motor 29, to which may be attached a position control device such as a rudder. This new position at which the motor shaft 33 stops is the position at which the potentiometer contact arms 37 and 38 on the potentiometers 35 and 36, respectively, become positioned so as to effect biases on the tubes 22 and 23 whereby the plate currents of the tubes 22 and 23 are equalized.

The motor shaft 33 will remain in this particular position as long as the particular positional control signal of paired voltages that established the shaft position is maintained in the filters 18 and 19 and primarily in the output of the device 1.

An analogous operational sequence occurs when a positional control signal of opposite sense to that considered above is intercepted by the receiver antenna 14 and is fed thru the receiver 15 to the control output device 16. In this situation signal of frequency f_3 in the filter 19 is stronger than signal of frequency f_2 in the filter 18 and the detector or rectifier 21 passes a stronger rectified signal to the grid 39 of the tube 23 than the detector or rectifier 20 passes to the grid 40 of the tube 22. Plate current in the winding 25 is also stronger than the plate current in the winding 24. In this instance the output of the generator 26 is of opposite sign to that obtaining for the signal first discussed.

In further comparison with the signal that was first discussed, the rotor 30 of the motor 29 turns in the opposite direction, and the motor shaft 33 turns to a definite control position that is opposite from the null position that is assumed by the motor shaft 33 as a result of the interception of the signal that has been previously discussed. The motor shaft 33 is held in its new null position by a process of balancing the plate currents in the tubes 22 and 23, as described.

The components of the present device, operating in the described manner, transmit and apply remotely, a positional control thru the agency of relative intensities of two alternating current signals of different frequencies.

The overall system that is contemplated hereby is adapted for transmitting and applying remotely a positional control by the agency of two or more pairs of alternating current components wherein all of the individual components are of different frequencies. By the adoption of the necessary equipment as disclosed herein for the use of a desired number of independent current components a desired number of independent remote controls can be used. The component frequencies in the composite control signal preferably are

not harmonically related, for minimizing mutual interference therebetween.

The use of a pair of signals that are differentiated by their frequencies to effect each control, preserves the signal intact thru accidental changes such as fading, fluctuations in power supply, and the like, whereby the ratio of the intensities of the two components remains intact. The characteristic of the present system whereby one component increases as the other component decreases provides twice the effectual signal change for a given position change as compared with a system using a single signal. These characteristics of the present system imparts improved positiveness in action and improved freedom from accidental interference.

It is to be understood that the circuits and the components therein that have been disclosed herein have been submitted for the purposes of illustrating and describing a suitably operating embodiment of the present invention and that similarly functioning modifications, changes and substitutions may be made therein without departing from the present invention as defined by the appended claims.

What I claim is:

1. In a control device of the character described, comprising in combination a first detector of a first alternating current signal, a first electronic amplifier tube, a first negative grid-bias supply, means applying the output of said first detector in the grid-cathode circuit of said first electronic tube in series opposition with said first negative grid-bias supply, a second detector of a second alternating current signal, a second electronic amplifier tube, a second negative grid-bias supply, means applying the output of said second detector in the grid-cathode circuit of said second electronic tube in series opposition with said second negative grid bias supply, an electric generator having a field coil that is split into a first portion and a second portion, means connecting said generator field coil first portion in the plate circuit of said first electronic amplifier tube, means connecting said generator field coil second portion in the plate circuit of said second electronic amplifier tube whereby the plate currents of said first and second electronic amplifying tubes give rise to magnetic fields in opposition, a motor receiving current from said generator and responsive in sense of rotation to the direction of the field of said field coil, control means activated by said motor, a first potentiometer means supplying negative bias to the grid-cathode circuit of said first electronic amplifier tube, a second potentiometer means supplying negative bias to the grid-cathode circuit of said second electronic tube, and means whereby said motor operates said potentiometers to effect equal overall grid voltages in said electronic amplifier tubes and whereby the motor is stopped in a position responsive to the two alternating current signals.

2. A control system comprising a control input device and a control output device, said control input device including a first source of oscillations having a first frequency, a second source of oscillations having a second frequency, means for simultaneously adjusting the amplitude of the first oscillations in one direction and the amplitude of the second oscillations in the opposite direction, a transmitter, and means for modulating said transmitter with the first and second oscillations; said control output device including a receiver for demodulating the output of said

transmitter, a first channel connected to the output of said receiver including first filter means for separating the first oscillations, first detector means connected to the output of said first filter means for rectifying the first oscillations, a first electronic amplifier tube, a first negative grid-bias supply, and means applying the output of said first detector in the grid-cathode circuit of said first electronic tube in series opposition with said first negative grid-bias supply, and a second channel connected to the output of said receiver including a second filter means for separating the second oscillations, second detector means connected to the output of said second filter means for rectifying the second oscillations, a second electronic amplifier tube, a second negative grid-bias supply, and means applying the output of said second detector in the grid-cathode circuit of said second electronic tube in series opposition with said second negative grid-bias supply, an electric generator having a field coil that is split into a first portion and a second portion, means connecting said generator field coil first portion in the plate circuit of said first electronic amplifier tube, means connecting said generator field coil second portion in the plate circuit of said second amplifier tube, whereby the plate currents of said first and second electronic amplifying tubes give rise to magnetic fields in opposition, a motor receiving current from said generator and

5
15
20
25
